CLAIM

The ornamental design for a portable garage as shown and described.

DESCRIPTION

FIG. 1 is a top view of a portable garage showing my new design in a closed configuration;

FIG. 2 is a left-side view of the present invention in the closed configuration;

FIG. 3 is a rear view of the present invention in the closed configuration;

FIG. 4 is a bottom view thereof;

FIG. 5 is a right-side view of the present invention in the closed configuration;

FIG. 6 is a front view of the present invention in the closed configuration;

FIG. 7 is a top front perspective view of the present invention in the closed configuration;

FIG. 8 is a top rear perspective of the present invention in the closed configuration;

FIG. 9 is a top view of the present invention in an open configuration;

FIG. 10 is a left side view of the present invention in the open configuration;

FIG. 11 is a rear view of the present invention in the open configuration;

FIG. 12 is a top front perspective view of the present invention in the open configuration;

FIG. 13 is a top rear perspective view of the present invention in the open configuration; and,

FIG. 14 is a right-side view of the present invention in the open configuration.

The broken lines illustrate portions of the portable garage that form no part of the claimed design.

1 Claim, 14 Drawing Sheets
